(57) **CLAIM**

The ornamental design for a refrigerator, as shown and described.

DESCRIPTION

FIG. 1 is a front perspective view of a refrigerator, showing our new design according to a first embodiment;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion 8 in FIG. 1;

FIG. 9 is a front perspective view of FIG. 1 in an alternate position;

FIG. 10 is a front view of FIG. 9;

FIG. 11 is a rear view of FIG. 9;

FIG. 12 is a left-side view of FIG. 9;

FIG. 13 is a right-side view of FIG. 9;

FIG. 14 is a top view of FIG. 9;

FIG. 15 is a bottom view of FIG. 9;

FIG. 16 is a front perspective view of a refrigerator, showing our new design according to a second embodiment;

FIG. 17 is a front view thereof;

FIG. 18 is a rear view thereof;

FIG. 19 is a left-side view thereof;

FIG. 20 is a right-side view thereof;

FIG. 21 is a top view thereof;

FIG. 22 is a bottom view thereof;

FIG. 23 is a front perspective view of FIG. 16 in an alternate position;

FIG. 24 is a front view of FIG. 16;

FIG. 25 is a rear view of FIG. 16;

FIG. 26 is a left-side view of FIG. 16;

FIG. 27 is a right-side view of FIG. 16;

FIG. 28 is a top view thereof of FIG. 16; and,

FIG. 29 is a bottom view of FIG. 16.

The even-dash broken lines illustrating portions of the refrigerator form no part of the claimed design. The dot-

(Continued)

dot-dash broken lines encircling enlargement portions of the claimed design form no part of the claimed design. A display device part of the refrigerator is rotatable to provide a portrait or landscape orientation of the display device part.

1 Claim, 29 Drawing Sheets
